(57) **CLAIM**

I claim the ornamental design for a platform for aquatic training and therapy, as shown and described.

DESCRIPTION

FIG. 1 is a perspective view of my new design for a platform for aquatic training and therapy of my design;

FIG. 2 is a front view thereof;

FIG. 3 is a rear view thereof;

FIG. 4 is a left side view thereof;

FIG. 5 is a right side view of thereof;

FIG. 6 is a top view of the platform for aquatic training and therapy of my design; and,

FIG. 7 is a bottom view.

The broken lines in FIG. 7 are for environmental purposes only and form no part of the claimed design.
